(57) **CLAIM**

The ornamental design for a controller, as shown and described.

DESCRIPTION

FIG. 1 is a front perspective view of a controller according to a first embodiment of the claimed design.

FIG. 2 is a rear perspective view of the controller of FIG. 1.

FIG. 3 is a top view of the controller of FIG. 1.

FIG. 4 is a bottom view of the controller of FIG. 1.

FIG. 5 is a front view of the controller of FIG. 1.

FIG. 6 is a rear view of the controller of FIG. 1.

FIG. 7 is a left side view of the controller of FIG. 1.

FIG. 8 is a right side view of the controller of FIG. 1.

FIG. 9 is a cross-sectional view of the controller of FIG. 1 taken along line 9-9 in FIG. 3.

FIG. 10 is a cross-sectional view of the controller of FIG. 1 taken along line 10-10 in FIG. 3.

FIG. 11 is an enlarged view of the enclosed portion in FIG. 9.

FIG. 12 is an enlarged view of the enclosed portion in FIG. 10.

FIG. 13 is a perspective view of the controller of FIG. 14 in a use environment.

FIG. 14 is a front perspective view of a controller according to a second embodiment of the claimed design.

FIG. 15 is a rear perspective view of the controller of FIG. 14.

FIG. 16 is a top view of the controller of FIG. 14.

FIG. 17 is a bottom view of the controller of FIG. 14.

FIG. 18 is a front view of the controller of FIG. 14.

FIG. 19 is a rear view of the controller of FIG. 14.

FIG. 20 is a left side view of the controller of FIG. 14.

FIG. 21 is a right side view of the controller of FIG. 14.

FIG. 22 is a front perspective view of a controller according to a third embodiment of the claimed design.

FIG. 23 is a rear perspective view of the controller of FIG. 22.

FIG. 24 is a top view of the controller of FIG. 22.

FIG. 25 is a bottom view of the controller of FIG. 22.

FIG. 26 is a front view of the controller of FIG. 22.

FIG. 27 is a rear view of the controller of FIG. 22.

FIG. 28 is a left side view of the controller of FIG. 22.

FIG. 29 is a right side view of the controller of FIG. 22.

FIG. 30 is a cross-sectional view of the controller of FIG. 22 taken along line 30-30 in FIG. 24; and,

FIG. 31 is an enlarged view of the enclosed portion in FIG. 30.

The interior portions of the controller illustrated with dashed hatch shading in FIGS. 9-12 and 30-31 of the drawings form

(Continued)

no part of the claimed design, but the exterior surfaces illustrated with solid lines in FIGS. 9-12 and 30-31 are claimed.

The dash-dot broken lines in FIGS. 3, 9-12, 24, and 30-31 of the drawings showing the section lines and enclosed portions form no part of the claimed design.

The dash-dash broken lines in FIG. 13 depict environmental subject matter only and form no part of the claim, while all other dash-dash broken lines in the drawings depict portions of the controller that form no part of the claimed design.

1 Claim, 29 Drawing Sheets
